DESIGN FOR A COMBINATION FLUORESCENT LIGHTING FIXTURE OR SIMILAR ARTICLE

Joseph Levy, Brooklyn, N. Y., assignor to Century Lighting, Inc., a corporation of New York

Application March 5, 1941, Serial No. 99,361

Term of patent 7 years

To all whom it may concern:

Be it known that Joseph Levy, a citizen of the United States and resident of New York city, in the county of Kings and State of New York, has invented a new, original, and ornamental Design for a Combination Fluorescent Lighting Fixture or Similar Article, of which the following is a specification, reference being had to the accompanying drawing, forming part thereof, in which Figs. 1 and 2 are front and end eleva-

tional views, respectively, of a combination fluorescent lighting fixture or similar article embodying the new design, and Fig. 3 is a bottom plan view thereof.

I claim:

The ornamental design for a combination fluorescent lighting fixture or similar article, as shown.

JOSEPH LEVY.
